Fig.4

FIGURE 1 is a top plan view of a hexagonal beverage carton showing my new design;

FIGURE 2 is a right side view of the carton shown in FIGURE 1; the left side view is identical to that shown in FIGURE 2.

FIGURE 3 is a frontal view of the carton shown in FIGURE 1; the rear view is identical to that of FIGURE 3.

FIGURE 4 is a perspective view of the embodiment of the invention illustrated in FIGURES 1, 2 and 3.

The bottom of the carton, in accordance with the instant invention, is a substantially planar surface.

The characteristic feature of the design resides in the multi-compartmented hexagonal carton comprising seven interior compartments with a central compartment being hexagonal in shape offset from the sides of the carton, each of the outer pockets comprising pentagonal figures, the apex of which is formed by the corners of the carton, and the base of same being formed by the sides of the inner hexagonal pocket, all as shown.

I claim:

The ornamental design for a hexagonal beverage carton, as shown and described.
